UNITED STATES PATENT OFFICE.

FRANK B. PEDLEY, OF POMONA, CALIFORNIA, ASSIGNOR OF ONE-HALF TO POMONA VALLEY MACHINE WORKS, A CORPORATION OF CALIFORNIA.

ROTARY HAND TOOL FOR CUTTING PLASTER CASTS.

Application filed November 29, 1926. Serial No. 151,368.

As may be inferred from the above title, this invention relates to a hand tool, capable of power operation, particularly designed for use in cutting through plaster casts, such as 5 are employed by surgeons, for the purpose of removing the same.

It is a general object of my invention to provide a rotary grinding or cutting element with means, preferably disposed in the same 10 plane therewith, for manually advancing said grinding or cutting element, during a power rotation thereof.

It is a further object of my invention to provide a hand-supported or hand guided 15 tool, comprising a grinding or cutting disc, with means adapting the same to be operated through a torque or flexible drive,—such as a protected chain of the general character currently employed in operating speedometers, 20 clipping shears, and the like. It is a further object of my invention to provide a hand tool of the general character referred to with a housing or main guard and/or with a subsidiary guard,—obviating risk or injury to an 25 operative or to a patient from whom a cast is to be removed; and preferred embodiments of my invention may include, in addition to a main housing integral with a handle such as is commonly provided upon a saw or plane, 30 a substantially cylindrical bearing boss, disposed centrally of said main housing or guard element. My invention also includes an advantageous arrangement of bearing elements, 35 and/or dust excluding elements and/or cutting-retaining elements,—some or all of these being secured independently of a removable member, such as a side plate comprised in the mentioned main housing.

The removal of plaster casts having been, 40 at best, a somewhat tedious and trying ordeal for patients, nurses and/or surgeons, it is a main object of my invention to obviate all necessity for the use of ordinary knives and/or rolling cutters, and all necessity for 45 the insertion of a wooden or metallic protecting element, between a cast and the flesh of a patient, to obviate risk of accidentally cutting said patient, during the removal of a cast; and preferred embodiments of my invention 50 (all forms thereof being capable of removing casts and wrappings thereon at a very rapid rate, and without the slightest physical or mental distress to a patient) may comprise means rendering the continuous operation of 55 a cutting element contingent upon an applica-

tion of thumb pressure, or the like, to a conveniently disposed switch.

Other objects of my invention—which appears to be suitable for numerous uses in addition to those above mentioned—may be best 60 appreciated from the following description of an illustrative embodiment of my invention, taken in connection with the appended claims and accompanying drawings, in which

Fig. 1 may be referred to as an elevational view, showing an embodiment of my invention as employed in that use for which said invention is primarily intended,—the removal 65 of a cast, with its wrappings, from a limb.

Fig. 2 is an elevational view, comparable 70 with Fig. 1, but drawn to a larger scale, and taken from an opposite direction,—a side plate being removed from a main housing or guard element, to show a thin grinding wheel, 75 employed as a rotary cutting element, there.

Fig. 3 is a transverse sectional view taken substantially as indicated by the line 3—3 of Fig. 2.

Fig. 4 is diagrammatic and intended merely 80 to emphasize the possibility of employing a fine-tooth usual or special saw or a milling cutter rather than a grinding wheel, in an organization of the general character referred to.

Fig. 5 is a detail view, taken substantially 85 as indicated by line 5—5 of Fig. 4, to indicate, on a larger scale, a preferred type of knife-like teeth, suitable for use upon a rotary saw, when used for the purpose of cutting through plaster casts and wrappings of cheese cloth, or the like,—said teeth preferably having a backward inclination.

Figures 1 to 3 inclusive, show a main housing 90 on guard element 11 as integral with a handle 12, comparable with an ordinary saw or plane handle, and disposed in the same plane with a disc-like rotary grinding or cutting wheel 13.

The main housing 11 may comprise a removable side plate 14, shown as secured by screws 15 over the open end face of a partially cylindrical casting 15' which includes also a substantially central bearing boss 16. Within the latter, I show a shaft 17 as supported by separate sets of rollers or ball bearings 18, 18', respectively engaging interior shoulders 19 and 19', provided by a central construction 20, within said bearing boss; and I show said boss as terminally provided with 105 110

- an apertured cap 21, having a central opening 22, sufficient not only to receive one end of a flexible tubular element 23 but to permit the connection of a flexible transmission member, such as a chain 24, extending therethrough, with a shaft 17,—as by a pinning together of coupling element 25 and 26, respectively terminating said chain and said shaft.
10. There being no very fundamental distinction between a fine-toothed circular saw and a thin grinding wheel, I show the housing 11^a, of Fig. 4, as provided with a rotary cutter in the form of a saw 13^a; and any suitable rotary cutter, whether in the form of a milling cutter or a saw or an emery wheel, or the like, may be secured to the shaft 17, or its equivalent, by means having the general character of the parts which are best shown 20 in Fig. 3.

Whether or not a dust excluding cap 27 is so interposed as to protect the bearings 18, 18', an enlargement or expansion 28 may be so disposed on shaft 17 that, upon the interposition of friction washers 29 and/or 29', with or without separate metallic or other washers 30 and/or 30', the tightening of a nut or nuts 31, upon a projecting inner end 32 of the shaft 17, may be relied upon to hold 30 the described cutting element, or its equivalent, in an intermediate plane, substantially parallel with inner walls 33, 33' provided by the housing 11^a (or 11') and plate 14.

To the main casting which includes housing 11 and handle 12, or to either of them, I may secure, as by means of screws 34, a subsidiary and removable guard element, such as a guard element comprising a flat or other finger 35 and an attachment plate 36,—these being shown as integrally connected by a web 37, of such restricted transverse thickness as to enable the same to advance through a kerf produced by the rotary cutter 13 (or 13^a); and it will be understood that this subsidiary guard element may, during the use of the described tool in cutting a cast from a patient's limb, ordinarily rest in contact with the skin of such limb, tending not only to protect the same from abrasion by said rotary cutter but to guide said cutter, relatively to the inner surface of the cast, holding said cutter to its work; and, assuming the said rotary cutter to be operated at a comparatively high speed (say, 4,000 to 55 6,000 R. P. M.) by means such as a small electric motor 38, current provided therefore (as, by way of a flexible cord 39, provided with a connecting plug 40) may be controlled by means such as a foot-operated or manual switch, included in said circuit and disposed within convenient reach of the user of my described tool,—as by providing, upon the handle 12, or its equivalent, a pressure button 41.

It will be obvious that, for certain uses to which my novel tool is also appropriate, the

described subsidiary guard comprising finger 35, shown as closely approached by the peripheral edge of the rotary cutter, may be modified or entirely omitted; and, although a fine-toothed circular saw, or any suitable 70 milling cutter, may be used as a rotary element in such embodiments of my hand tool as may be used in the cutting of wall board or lumber or metal, in order to adapt a rotary saw blade to cut not only through the 75 plaster of a cast but through the fabric wrappings thereon, I may so sharpen a rotary saw as to form separate but suitably set separate and backwardly inclined blades from the teeth thereof,—thinning the more inclined 80 or forward edges of the mentioned teeth, and preferably rotating the resultant cutter in the direction indicated by the arrows 43.

In the cutting of entirely dry castings and fabric wrappings, a thin emery grinding wheel 13, only a restricted portion of its cutting edge being exposed beyond the mentioned housing, is found to operate very satisfactorily; but a saw-like rotary cutter may be more advantageous, as tending to obviate 90 clogging, in cutting through moist or slightly plastic materials,—the exact character of the teeth selected being dependent either upon the consistency of the material or upon the direction of cut. In any event, it will be 95 obvious that the described tool is capable of very expeditiously removing a cast or form without the slightest distress to a patient or operative; and that, in case the rotary cutter does become clogged, cleaning may be easily 100 effected by the removal of the plate 14, or its equivalent, without disturbing the shaft and bearings.

The disposition of the handle 12 in the same plane with the rotary cutter is highly advantageous as facilitating the manipulation of the described tool with one hand, as in the case of an ordinary saw or plane.

Although I have herein described a single and complete embodiment of my invention 110 disclosing alternative cutting elements, it should be understood that not only various features thereof may be independently used but also that numerous modifications might be made, by those skilled in the art to which 115 this case relates, without involving the slightest departure from the spirit and scope of this invention, as the same is indicated above and in the following claims.

I claim as my invention:

1. A rotary tool for cutting plaster casts which comprises: a partially cylindrical casting having a substantially open end face and provided with a bearing boss extending oppositely from said open face; bearings mounted in said bearing boss; a shaft rotatably supported by said bearings; a disk-like rotary cutting element mounted on said shaft and adapted to rotate in the partial cylindrical section of said casting; a cover plate remov- 120

130

ably mounted on said casting over said open end face and adapted to provide a housing for said cutting element; a handle mounted on said housing; and power means for imparting rapid rotation to said cutting element.

2. A rotary tool for cutting plaster casts which comprises: a partially cylindrical casting having a substantially open end face and provided with a bearing boss extending oppositely from said open face; bearings mounted in said bearing boss; a shaft rotatably supported by said bearings; a disk-like rotary cutting element mounted on said shaft and adapted to rotate in the partial cylindrical section of said casting; a cover plate removably mounted on said casting over said open end face and adapted to provide a housing for said cutting element; a handle mounted on said housing; power means separate from said housing for imparting rapid rotation to said cutting element; and a guard mounted on said housing and extending therebelow.

3. A rotary tool for cutting plaster casts which comprises: a partially cylindrical casting having a substantially open end face and provided with a bearing boss extending oppositely from said open face; bearings mounted in said bearing boss; a shaft rotatably supported by said bearings; a disk-like rotary cutting element mounted on said shaft and adapted to rotate in the partial cylindrical section of said casting; a cover plate removably mounted on said casting over said open end face and adapted to provide a housing for said cutting element; a motor separate from said tool for imparting rapid rotation to said cutting element; flexible driving means interposed between said motor and said shaft; and a handle mounted on said housing.

4. A rotary tool for cutting plaster casts which comprises: a partially cylindrical casting having a substantially open end face and provided with a bearing boss extending oppositely from said open face; bearings mounted in said bearing boss; a shaft rotatably supported by said bearings; a disk-like rotary cutting element mounted on said shaft and adapted to rotate in the partial cylindrical section of said casting; a cover plate removably mounted on said casting over said open end face and adapted to provide a housing for said cutting element; a handle mounted on said housing; power means separate from said housing for imparting rapid rotation to said cutting element; and a guard mounted on said housing and extending therebelow.

5. A rotary tool for cutting plaster casts which comprises: a partially cylindrical casting having a substantially open end face and provided with a bearing boss extending oppositely from said open face; bearings mounted in said bearing boss; a shaft rotatably supported by said bearings; a disk-like rotary cutting element mounted on said shaft and adapted to rotate in the partial cylindrical section of said casting; a cover plate removably mounted on said casting over said open end face and adapted to provide a housing for said cutting element; a handle mounted on said housing; power means separate from said housing for imparting rapid rotation to said cutting element; and a guard mounted on said housing, provided with an element which extends into and is adapted to advance through a kerf cut by said cutting element.

In testimony whereof, I have hereunto set my hand at Los Angeles, California, this 20th day of November, 1926.

FRANK B. PEDLEY.
